AUTOMATIC DIE CASTING APPARATUS

Filed Aug. 25, 1931

2 Sheets-Sheet 2

FIG. 2.

The diagram illustrates a mechanical assembly, likely a pump or valve mechanism. It features a central cylinder with a plunger. Various components are labeled with letters:

- Inlet:** A port on the left side.
- outlet:** A port on the right side.
- Pressure:** A vertical line indicating pressure application.
- Drive:** A handle or lever at the bottom left.
- Component labels:** a, b, c, d₁, d₂, e, f, g, h, i₁, i₂, i₃, k, l₁, l₂, l₃.
- Output ports:** B₁, B₂, C.

The internal structure includes a plunger, a piston rod, and various valves and seals. The assembly is designed to handle fluid pressure and be driven by a mechanical input.

AUTOMATIC DIE-CASTING APPARATUS

Karl Friedrich Wagner, Stuttgart, Germany, assignor, by mesne assignments, to Magnesium Development Corporation, Newark, N. J., a corporation of Delaware

Application August 25, 1931, Serial No. 559,249
In Germany August 28, 1930

10 Claims. (Cl. 22—69)

This invention relates to a method of and means for assuring the safe working of automatic pressure die-casting apparatus.

In connection with the mechanical production of pressure die-castings, the need arose, at an early period, for safety measures to prevent the unintentional performance of individual working stages, or their performance in incorrect serial order. The desire for such measures has led to numerous proposals, most of which naturally relate to the safe operation of manual apparatus and only a few to automatic pressure die-casting apparatus.

In contradistinction to the foregoing, the present invention relates to a method of and means for assuring the safe working of automatic pressure die-casting apparatus, especially those with hydraulic control, and in which most of the operations, and particularly the closing and opening of the parts of the mold, and also the starting and stopping of the injection pressure, are actuated or initiated in a definite serial order and at definite intervals, for example by a single or several rotating cam shafts. The arrangements of the present invention differ fundamentally from those previously suggested, in that the problem of preventing a succeeding working stage from being initiated until the preceding stage has been correctly performed, or quite completed, is propounded and solved for the first time herein.

Safety measures of this kind are chiefly needed to prevent:

(1) The injection pressure being turned on when the halves of the mold are not completely closed, or until a tight connection has been established between the mold and the injection nozzle. It is particularly essential that the injection pressure should not come into action before the sealing pressure, requisite for closing and locking the halves of the mold, and the injection nozzle connection with the mold has been attained, since otherwise the admission of the injection pressure would force the fluid metal through any openings between the mold halves or between the injection nozzle and the mold;

(2) The detachment of the mold from the injection nozzle, so long as any positive pressure still exists in the pressure chamber opening into the injection nozzle, since otherwise, the fluid metal would be projected through the nozzle into the atmosphere.

According to the present invention these requirements are taken into consideration in that the operation of the apparatus is stopped in a

positive manner, when the conditions necessary for the safe continuance of operation are absent and particularly, when the stage of operation to be safeguarded has not been correctly and completely performed. The stopping of the apparatus is preferably effected by providing between the working stages concerned, a separate safety stage which is also actuated by the control mechanism of the apparatus and stops the same when necessary.

A preferred method of achieving this result consists in providing a safety stage in the form of a reciprocatory pawl which, when the conditions assuring safety are lacking, engages a lever which throws out the clutch of the control mechanism, said pawl however being drawn-in when the conditions are normal, so that it cannot actuate the lever.

In order to more clearly understand the nature of the present invention, reference is made to the accompanying drawings, which illustrate diagrammatically and by way of example, two embodiments of apparatus suitable for carrying out the invention, and in which:

Fig. 1 affords a view of the device (A) which stops the apparatus, and also of the members (B₁, B₂ and C) actuating said device.

Fig. 2 shows a special improved embodiment of the device for stopping the machine when occasion requires.

With reference to Fig. 1 a is one of a series of valves which control the respective stages of operation of the machine, said series of valves being arranged in a block so as to form a pressure distribution system. The valves are operated in a suitable manner, as shown in connection with valve a, through the medium of tappets b and rollers c rotatably mounted at the ends of the tappets and in contact with cams d mounted on the cam-shaft e. According to the invention six valves are provided in the pressure distribution system for actuating the various safety stages, said valves being arranged in pairs, and each pair serving to actuate a safety pawl by means of controlling the hydraulic pressure acting on the pistons l₁, l₂ and l₃, to the rods of which the pawls i₁, i₂ and i₃ are attached.

The pairs of cams serving to actuate the respective safety pawls are so designed and positioned on the cam shaft e that on completion of each of the working stages to be safeguarded, for example, closing the mold and positioning it over the injection nozzle, establishing the necessary hydraulic locking pressure for the mold halves, and relieving the injection pressure in the

pressure chamber, the proper pair of valves is actuated.

The pawls i_1 , i_2 and i_3 are normally held in engagement with a suitable clutch lever g by means of tension springs k . The clutch lever g is constructed in the form of a bell crank, one arm of which is forked, and as shown in Fig. 1, the bell crank is pivotally mounted in such a manner that its forked arm engages the dog clutch f , of any suitable conventional design, while the arm, which is actuated by the pawls when required, is normally held, by means of a counter spring h , to keep the clutch engaged.

The mechanism B_1 which sets the safety device in operation is actuated when the parts of the mold are closed and the mold is firmly seated, as a unit, on the injection nozzle. For this purpose, there is provided an intermediate member m , positioned on the mold o which, in turn, rests on the press table n containing the injection nozzle, not shown. A striker pin p , rigidly secured to the member m , provides for actuating a single lever q which is attached by means of a rod or the like to the pawl i_1 , whereby the pawl is drawn downwardly only when the mold is completely closed.

The mechanism B_2 of the device is actuated when the necessary locking or working pressure for tightening up the halves of the mold and, if necessary, for establishing a tight connection between the mold and the injection nozzle, has been attained.

The mechanism B_2 comprises a cylinder which houses a piston r which moves against the action of a spring s , standardized or designed to withstand locking pressure. The other end of the cylinder communicates with the high-pressure stage of the locking cylinder of the machine, so that the hydraulic pressure applied for tightening up the mold, in each case, acts on this side of the piston. When the locking pressure has been attained, the piston compresses the spring and thus draws the pawl i_2 by means of a suitable tractive member.

The mechanism C which prevents the mold from being removed from the press table carrying the nozzle or nozzles, not shown, before the injection pressure in the pressure chamber has been completely relieved, is built into the vent pipe which opens into the delivery side of the pressure chamber and is evacuated by a valve in the usual manner. In the neutral position, the piston t is retained by a spring u , in a position in which it closes the vents w . On the pressure-relief valve, not shown, being opened, the compressed air overcomes the slight force of the spring and drives the piston far enough to enable said air to escape through the vents w . At the same time, the piston actuates the lever v and by so doing, enables the pawl i_3 to be drawn downwardly by means of a suitable tractive member, thus allowing the mold to be removed from the press table.

The arrangement operates in the following manner:

So long as the mechanisms B_1 , B_2 or C operate to pull downwardly on the corresponding pawls, the reciprocating movements of the pistons l_1 , l_2 or l_3 cannot actuate the clutch lever so as to disengage the clutch inasmuch as the pawls slide freely under the lever.

However, when any one of the members B_1 , B_2 or C remains inactive, that is to say, when the conditions for the safe continuance of the working operations of the apparatus are not fulfilled,

the corresponding pawl engages the lever g during the reciprocating movement of the corresponding piston l , thus causing the lever to open the clutch and automatically stop the machine.

The embodiment of the stop mechanism (A) shown in Fig. 2 represents an improvement over that described above, inasmuch as only a single piston l , and a pair of valves a in the distributor are needed for actuating the throw-off lever g . The valve pair is actuated by two cams d_1 and d_2 in each case, and thus reciprocates the piston l . The forked end of the piston carries the pawls i_1 , i_2 , and i_3 , which in turn, act on the long arm of the lever g , in the manner already described. However, since each of the safety devices B_1 , B_2 and C can only be actuated during the corresponding working stage, means must be provided to prevent the lever g from being engaged, during the reciprocating movement of the piston, by the pawls which are inactive during such stage. This is accomplished by means of the cams x_1 , x_2 and x_3 , which are also mounted on the cam-shaft e and act directly on the several pawls, the cams being of such contour that in each case, they release the corresponding pawls only during the period in which the safety device connected with the pawl can be actuated at all, while otherwise they keep the pawls in the depressed position and thus prevent them from engaging the long arm of the lever g .

I claim:

1. A safety device for automatic pressure die-casting apparatus in which a plurality of working stages are initiated in definite serial order by means of an automatically driven control mechanism, comprising means for disengaging said control mechanism from its driving means, and means for causing said disengaging means to act at the termination of any one of the working stages on failure of such working stage to complete its function.

2. A safety device for controlling automatic die-casting apparatus in which a plurality of working stages are performed in definite sequence, comprising a pressure distribution system clutch-connected to a driving means, an element associated with each working stage of the pressure distribution system, said elements being adapted to disengage the clutch on failure of any one of the working stages to complete its function.

3. A safety device for controlling automatic die-casting apparatus in which a plurality of working stages are performed in definite sequence, comprising a pressure distribution system clutch-connected to a driving means, a plurality of pawls equal in number to the number of working stages, said pawls being actuated by the pressure distribution system and adapted to disengage the clutch between the driving means and the pressure distribution system upon failure of any one of the working stages to complete its function.

4. A safety device for automatic pressure die-casting apparatus in which a plurality of working stages to be safeguarded are performed in definite sequence, said safety device comprising a plurality of pressure-operated safety pawls equal in number to the working stages, a clutch mechanism connecting a means for actuating the pawls to a driving means, connecting elements between each of the pawls and a corresponding portion of the die-casting machine adapted to perform the working stages, said pawls being adapted to normally engage said clutch mechanism to interrupt the driving means on failure of any one of the working stages to complete its

- function, and said connecting elements preventing engagement of the clutch lever by said pawls so long as the working stages complete their functions.
5. A safety mechanism for automatic pressure die-casting apparatus in which the working stages, closing the mold and seating the same upon an injection nozzle, locking the mold and establishing a tight connection between the mold and the injection nozzle, and relieving the pressure for injecting molten metal through the injection nozzle into the mold, are performed in the order named; said safety mechanism comprising means associated with elements of the die-casting apparatus for performing the above-mentioned working stages, said associated means being connected with safety pawls for safeguarding the performance of the working stages in definite sequence, a cam shaft for actuating the safety pawls across a clutch lever controlling the operation of said cam shaft, means connecting said pawls with said elements of the die-casting machine for performing the working stages, said connecting means being adapted to withdraw the safety pawls out of engagement with said clutch lever when the working stages are correctly performed, said pawls being adapted to disengage said clutch lever and interrupt the operation of the die-casting apparatus on failure 30 of any one of the above-mentioned working stages to perform its function.
6. A safety mechanism for controlling the working stages of a pressure-operated die-casting apparatus in which the working stages, closing and seating a mold upon an injection nozzle, locking the mold and establishing a tight connection between the mold and the injection nozzle, and relieving the pressure for injecting molten metal into the mold, are performed in the order named; said safety mechanism comprising devices associated with those portions of the die-casting apparatus which are employed in the direct performance of the above-mentioned working stages, a series of cams operating in timed relationship with respect to the working stages, said cams being adapted to control through valves the reciprocation of a series of safety pawls equal in number to the number of working stages, an oscillatory clutch lever adapted to disengage the cams from a driving means, said clutch lever being normally resiliently pressed into operative engagement, said safety pawls being adapted to engage said clutch lever to disengage the cams from the driving means on failure of any one and all 55 of the working stages.
7. A safety mechanism for controlling the working stages of a pressure-operated die-casting apparatus in which the working stages, closing and seating a mold upon an injection nozzle, locking the mold and establishing a tight connection between the mold and the injection nozzle, and relieving the pressure for injecting molten metal into the mold, are performed in the order named; said safety mechanism comprising a pressure distribution system having a series of valves arranged in a housing, a cam shaft associated with said valves and adapted to actuate the same in timed relationship with respect to the working stages, a clutch connecting said cam shaft to a driving means actuating said automatic die-casting apparatus, a clutch-manipulating lever associated with said clutch, a series of cylinders and pistons in combination with said pressure distribution system, said pistons being adapted to
- be reciprocated in timed relationship with said working stages, safety pawls pivoted to connecting rods extending from said pistons, said pawls being normally adapted to engage said clutch lever to disengage the same, means associated with said pawls and elements of the die-casting apparatus to withdraw the pawls from engagement with said clutch lever, whereby the pawls are held out of engagement with the clutch lever so long as all of the working stages are properly performed.
8. A safety device adapted to control the sequence of operations in an automatic die-casting apparatus having a mold, an injection nozzle, means for effecting a tight connection between said mold and said injection nozzle, pressure means for injecting molten metal into said mold through said injection nozzle, means for relieving the pressure in said pressure means when said mold is filled, means for disconnecting the said injection nozzle from said mold, and driving means for operating the aforesaid means in sequence; said safety device comprising a clutch mechanism for connecting said driving means to a power shaft, a reciprocatory member adapted to disengage said clutch, and means for operating said reciprocatory member upon the failure of any of the aforesaid means to complete its function.
9. A safety device adapted to control the sequence of operations in an automatic die-casting apparatus having a mold, an injection nozzle, means for effecting a tight connection between said mold and said injection nozzle, pressure means for injecting molten metal into said mold through said injection nozzle, means for relieving the pressure in said pressure means when said mold is filled, means for disconnecting the said injection nozzle from said mold, and driving means for operating the aforesaid means in sequence; said safety device comprising a clutch mechanism for connecting said driving means to a power shaft, said clutch mechanism comprising a bell crank lever one arm of which is adapted to open and close said clutch, and the other arm adapted to actuate the first-mentioned arm, safety pawls adapted to engage said actuating arm, said pawls being connected to a piston for reciprocatory motion, a cylinder enclosing said piston, a valve and valve housing in association therewith, said valve being actuated by the drive shaft whereby pressure is admitted to said cylinder to reciprocate said safety pawls, and means mounted on said drive shaft in contact with said safety pawls to hold them out of engagement with said actuating arm, whereby the clutch may be held in engagement.
10. A safety device for controlling automatic die-casting apparatus in which a plurality of working stages are performed in definite sequence, comprising a plurality of safety pawls mounted for reciprocatory movement, pressure-operated means for reciprocating said pawls, said pressure-operated means being actuated through a clutch by the die-casting machine driving means, a clutch lever associated with said clutch, said pawls being adapted to engage said clutch to disengage the pressure-operated means from the die-casting machine driving means, and means associated with the pawls and driving means for holding the pawls out of engagement with said clutch lever.

KARL FRIEDRICH WAGNER.
